HEAT EXCHANGER

George B. Farkas, Jackson Heights, N. Y., assignor to American Locomotive Company, New York, N. Y., a corporation of New York

Application September 26, 1945, Serial No. 618,623

7 Claims. (Cl. 257—239)

1

This invention relates to heat exchangers and more particularly to a structure including a bundle of heat exchange tubes and end tube sheets and headers for the tubes, and a control for the structure for effecting descaling of the tubes.

This invention is an improvement of the invention disclosed in the patent to Jacocks et al., No. 1,855,552, dated April 26, 1932, wherein descaling of tubes is effected by bowing and unbowing the tubes to flake off scale deposits thereon.

According to the invention of the aforesaid patent, means for positively causing bowing of the tubes is provided. However, means for insuring unbowing of the tubes is not provided. This presents various disadvantages. It prevents maximum bowing and unbowing of the tubes and therefore decreases the efficiency of the descaling operation. Furthermore it results in increasing the cross-sectional area of the tube bundle when the tubes do not unbow to their original condition, which may prevent the withdrawal of the structure through an opening provided in the heat exchanger shell where the structure is employed in a shell type of exchanger, the withdrawal being periodically necessary for the purpose of cleaning and repairing the parts.

The object of the present invention is to insure the tubes of the bundle assuming their original position and having maximum unbowing during contraction so that there will be no increase in cross-sectional area of the bundle at final contraction of the tubes and so that maximum bowing and unbowing may be effected during thermal expansion and contraction of the tubes.

Referring to the drawings forming a part of this application, Figure 1 is an elevation in partial vertical central section on the line I—I of Fig. 2, of a shell type heat exchanger embodying the present invention; Fig. 2 is a section on the line II—II of Fig. 1, parts being broken away and other parts being shown in full; Fig. 3 is an enlarged section on the line III—III of Fig. 2, a part being shown in dot and dash lines; Fig. 4 is a foreshortened section on the line IV—IV of Fig. 3, parts being broken away and parts being shown in full; Fig. 5 is an enlarged detail shown fragmentally and partly in section; Fig. 6 is a view, similar to Fig. 2, showing the tube bundle bowed, the tie rods straightened out, and the associated elements moved to changed position when the apparatus has been heated in normal operation; Fig. 7 is a section on the line VII—VII of Fig. 2 showing the apparatus in original or room temperature position; Fig. 8 is a section on the line

2

VIII—VIII of Fig. 6 showing the tie rods in straightened out position and the plate shoulders contiguous thereto; Fig. 9 is a section on the line VIII—VIII of Fig. 6 showing the tie rods in straightened-out position but with the plates moved laterally therefrom upon the application of additional heat to the tubes; and Fig. 10 is a detail view showing the stop means in extended position.

The present invention, for illustrative purposes, is shown in connection with a shell type of heat exchanger and will be so described, but it may be used with other types of heat exchangers, as for instance with the cooling tower shown in the aforesaid Jacocks et al. patent. It has been stated that the present invention is an improvement of the heat exchanger of the Jacocks et al. patent. Therefore various features will be briefly described and reference may be had to the Jacocks et al. patent for a fuller understanding thereof.

The invention, for convenience, is illustrated in connection with a shell type of heat exchanger. The shell, which is horizontally disposed, is indicated by the reference numeral 1. It is supported by legs 2, has a water inlet 3, a steam outlet 4, drains 5 and an outwardly flanged opening 6 at the front.

The structure of the present invention is indicated generally by the reference numeral 7 and includes a bundle of fluid conducting tubes 8 vertically divided into two groups 9 and 10. The tubes are secured at their rear ends in a tube sheet 11 covered by a header or cap 12, the tube sheet and header being secured together by a split clamp ring 13 of usual construction, the clamp being provided with the usual set screws 14.

The tubes are secured at their forward ends in a tube sheet 15 which is covered by a header or channel 16. The channel at its rear end is outwardly flanged and is secured to the flange of the opening 6, with the tube sheet 15 interposed, by another clamp ring 13' having set screws 14'. The channel is outwardly flanged at its forward end and covered by a plate 17, the plate being secured to the forward flange by another clamp ring 13'' having set screws 14''. The channel is divided interiorly by a horizontal partition 18 into a large upper compartment 19 which communicates with and supplies steam to most of the tubes and has a steam inlet 20, and a relatively small lower compartment 21 which communicates with the remaining relatively small number of tubes, and which is provided with an outlet 22.

The steam travels through the upper tubes

in the direction of the arrows from the compartment 19 to the header 12, and from the header 12 through the small number of tubes at the bottom to the compartment 21. It will be understood that the various outlets and inlets before mentioned are flanged for connection with suitable piping in the usual manner.

The structure 1, and the control for the expansion and contraction of the tubes which will later be described, form a unit which is secured at its front end portion to the front end of the shell by the clamp ring 13' in the manner aforesaid. Except for this connection and the pipe connections (not shown) for the steam inlet 20 and outlet 22, the unit is otherwise free and therefore floats at its rear end.

The structure is removable from the shell by merely removing the clamp ring 13' and the aforesaid pipe connections. This frees the channel for removal and leaves the remainder of the structure and the control free for removal from the shell, the control and structure parts to the rear of the tube sheet 15 being free for withdrawal through the opening 6 in the shell for repair and cleaning.

Where the invention is used in connection with a shell type of heat exchanger, as in the present instance, it is necessary that the bundle of tubes does not increase in cross-sectional area due to permanent bowing so that the unit cannot be removed and replaced through the opening 6 which is necessarily of limited area, and it is one of the objects of this invention to insure against this increase in cross-sectional area of the bundle of tubes.

The shell is further provided with a base support for the unit. To this end a comparatively short longitudinally extending track 23 is welded to the bottom of the shell interiorly thereof of adjacent the center. This track serves both as a guide and as a support for a part of the tube control, as will later more fully appear. It is contracted at its forward end 24 as shown in Fig. 3, to serve as a finder. The base support further includes a track 25 at each side of and spaced from the track 23 and extending longitudinally of the shell. The tracks 25 extend from the opening 6 rearwardly to the header 12. The tracks 25 are welded to spaced brackets 26 which are in turn welded to the bottom of the shell interiorly thereof. The tracks 25 are for supporting the unit in a manner later to be described, and for facilitating removal of the unit from the shell and replacement therein.

The structure 1 further includes a transversely disposed pair of aligned substantially semi-circular vertical plates 27. There is a substantially similar pair of plates 28 at each side of and longitudinally spaced from the pair of plates 27. The tubes 8 are staggered and arranged in horizontal rows. All but the two lowermost rows open into the compartment 19, and the two lowermost rows, which are spaced from the upper rows, open into the compartment 21. The plates have orifices 29 arranged similarly to the arrangement of the tubes and through which the tubes freely extend.

The plates 27 are disposed at the longitudinal center of the tubes and each pair of plates 28 is disposed midway between the plates 27 and the adjacent tube sheet. There is a plate 27 and a plate 28 on each side thereof for each of the groups of tubes 9 and 10. The plates support the tubes and to this end each of the plates 27 is provided with a leg 30, and each of

the plates 28 is provided with a leg 31. The legs rest upon the tracks 25 in sliding relation therewith whereby the unit may be drawn along the tracks for removal and replacement thereof as aforesaid.

The plates are fastened to the tube sheets by tie rods in the following manner: Referring more particularly to Figs. 3 and 4, each plate 28 at the right of the plates 27 is tied to the tube sheet 15 by two spaced upper and two spaced lower rods 32. The rods are threaded into the tube sheet 15, extend through the respective plates 28 and are secured thereto by nuts 33 at each side of the plate through which the rod passes.

Each of the plates 27 and the aligned plate 28 to the left thereof are tied to the tube sheet 11 by two spaced upper and two spaced lower rods 34. The rods are threaded into the tube sheet 11, 20 extend through the respective plates 28 at the left and the respective plates 27 and are secured thereto by nuts 35 at each side of the respective plates 28 and 27 through which the rod passes.

The plates 27 are not tied to the plates 28 at 25 the right thereof. This is to permit the free bowing of the tubes as will presently appear. The plates 28 at the right of the plates 27 are thus held in fixed relation to the tube sheet 15, and the plates 27 and the plates 28 to the left thereof are held in fixed relation to each other and to the tube sheet 11, that is to say the respective plates are held against movement longitudinally of the tubes relative to their respective tube sheets.

35 The plates of each pair have vertical adjacent inner edges 36 and opposite outer substantially semi-circular edges 37. Each of the plates has upper and lower inclined corners 38 at the ends on its edge 36 providing on each pair of plates a 40 top and bottom V-shaped groove 39. The plates 28 have straight horizontal upper edges 40 extending from their respective corners 38 to their respective outer semi-circular edges 37. The plates 28 have straight horizontal lower edges 41 45 extending from their respective corners 38 to their respective legs 31. The plates 27 are formed somewhat differently than the plates 28. The plates 27 at their upper and lower ends, and adjacent their corners 38, have shoulders 42, each shoulder having a horizontal wall 43 and a vertical abutment wall 44.

The tubes of each group 9 and 10, when bowed, 50 are bowed laterally outward, and the respective plates moved therewith laterally outward correspondingly, the plates of each pair, during such bowing, spreading apart along their vertical inner edges 36. The tubes are preferably straight tubes as shown, and will be so considered.

The control instrumental in effecting the bowing of the tubes is composed of two separate 55 means or devices. One of the means or devices is for bowing the tubes when under thermal expansion, and is indicated generally by the reference numeral 45. The other means or device is 60 to insure the tubes being restored to their normal condition when under thermal contraction, and is indicated generally by the reference numeral 46.

The device generally indicated as 45, includes 65 four tube-bowing members 47, one at the top and one at the bottom of each of the tube groups 9 and 10. Each of the members 47 is secured to the tube sheets 11 and 15, and is bent inwardly to form an angle 48 at its center, that is to say 70 at its correlated plate 27. It seats in its corre-

lated shoulder 42 and bears against the abutment wall 44 of the shoulder at the angle. It is adjacent to its correlated edge 40 or 41, as the case may be, of the plates 28.

Each member 47 includes a bar 49 rectangular in cross section and containing the angle 48. The bar is secured at its rear end, as by welding or otherwise, to the tube sheet 11, and is secured at its forward end to a turnbuckle 50.

The turnbuckle is best shown in Fig. 5 and 10 includes a forked rod 51 in which fork the forward end of the bar 49 is fitted and welded. The rod 51 at its opposite end is provided with a head 52. The turnbuckle further includes a threaded rod 53 which is screwed at its forward end in the tube sheet 15 and a member 54 which is made in two pieces 55 and 56 welded together, the piece 55 having a threaded bore 57 screwed onto the threaded rod 53 at its rear end. The other piece 56 is bored to provide a shoulder 58. The rod 51 extends into the bore with the head 52 seated against the shoulder 58. By turning the member 54 the tube-bowing member 47 may be tensioned to the extent desired.

It is intended that the descaling take place during the normal operation of the heat exchanger, but if desired, fluid of a higher temperature than that used for the normal operation may be periodically supplied through the inlet 20 alternately with a supply of cold fluid into 30 the shell through an inlet 3' to provide an independent quick method for bowing and unbowing the tubes for descaling them.

The device 45 operates as follows: As the tubes expand, the header 12 is forced rearwardly which movement causes the four tube-bowing members 47 to start to straighten. Their angles 48, being in engagement with their respective abutment walls 44, simultaneously, during straightening, force each plate 27 laterally outward thereby causing the tubes of each group 9 and 10 to bow laterally outward due to their connection with these plates 27. The plates 28 follow the tubes during their bowing.

This forced bowing of the tubes continues until the tube sheet 11 and header 12 are stopped in their rearward movement. This may be accomplished in several ways, for instance by having an abutment (not shown) fixed to the shell at the rear of the header 12. The header in this way may be stopped before the members 47 are completely straight.

However in the present instance the members 47 are relied upon for stopping the aforesaid rearward movement, and this is effected upon the members 47 becoming straight. After this any further tube expansion that might occur causes automatic further bowing of the tubes during which further bowing the abutment walls 44 move laterally outward away from engagement with their respective angles 48.

During contraction of the tubes the reverse operations take place in an obvious manner. The tubes begin to unbow and if the abutment walls 44 have separated from their respective members 47 the unbowing continues until the abutment walls 44 engage their respective members 47. Thereafter further contraction of the tubes causes the further unbowing and causes the abutment walls 44 to force their respective members 47 inward, bending the members 47 to form the angles 48.

During these unbowing operations the header 12, the tube sheet 11 and the adjacent tube ends move forwardly to their original positions. The 75

device 45 and its operation is similar to that of the before mentioned patent. However, as aforesaid, at times the unbowing to return the tubes to their original condition is not completed and instead, after the tubes have prematurely stopped unbowing, further contraction thereof results in moving the header 12, tube sheet 11 and adjacent tube ends further forwardly past their normal positions with the disadvantages following that have already been mentioned.

It is the object of this invention to prevent this and to insure the intended unbowing of the tubes. The device 46, best shown in detail in Fig. 4, accomplishes this. It includes two telescopic members 59, extending longitudinally parallel to the tubes between the tube sheets 11 and 15. The members 59 are disposed one above the other in the central vertical plane of the bundle of tubes, the top member 59 extending into the top V-shaped grooves 38 and the bottom member 59 extending into the bottom V-shaped grooves 39. The top member 59 is disposed between the top tube-bowing members 47 above the tubes, and the bottom member 59 is disposed between the bottom tube-bowing members 47 below the tubes.

Each member 59 includes a long tube 60 secured at one end, as by welding, indicated at 60a, to one of the tube sheets, in the present instance the tube sheet 15, and a short tube 61 extending into the opposite end of the tube 60 in sliding relation therewith. Tube 61 is secured, as by welding, indicated at 60b, at its outer end to the tube sheet 11.

35 The track 23 is disposed forwardly of the plates 27 and the tubes 60 are secured together by a plate 62 disposed above the track 23 and extending longitudinally between the tube groups 9 and 13. The plate 62 is secured to the tubes 60, as by 40 welding, as indicated at 62c, and serves to prevent the members 59 from bending, and further supports the top member 59 from the bottom member 59.

A post 63 is secured to the lower tube 60, as 45 by welding. The post is in line with the track 23 and includes two side plates 64 extending from the lower tube 60 downwardly to and overlapping the sides of the track 23 and a cross plate 65 which rests upon the track 23 thus supporting 50 the bottom member 59. When the unit is removed from the shell the plate 65 merely slides along the track 23 until it is free thereof. When the unit is replaced the plate 65 meets and rides upon the track 23, the contracted end 24 of the 55 track assisting the plate 65 in finding the track 23 if found necessary.

The tubes 60 are of a length equal to the distance between the tube sheets 11 and 15 when in their normal relative positions so that their 60 telescoped ends which are adjacent the tubes 61 abut the tube sheet 11 when it is in its normal position.

The operation of the device 46 is simple. When tubes 8 expand thermally, tube sheet 11, header 12, and the short tubes 61 move rearwardly as a unit away from the tubes 60 which, as previously explained, are anchored to tube sheet 15. The longitudinal separation of tube sheet 11 from the tubes 60 is illustrated in Fig. 10 although the amount thereof has been exaggerated for purposes of illustration. The extent of such separation will be limited by device 45 when members 47 have reached straight positions. Upon thermal contraction of tubes 8, tube sheet 11, header 12, and the short tubes 61

move forwardly as a unit toward the tubes 60, and tubes 61 telescope into tubes 60. When tube sheet 11 encounters tubes 60, the latter will function to stop any further forward movement of the former. If tubes 8 are still in bowed condition when sheet 11 is stopped by tubes 60, they will still continue to contract to a straight condition. Upon reaching such a straight condition, however, the tubes will be prevented from contracting any further and of course there will be no further bowing.

While there has been hereinbefore described an approved embodiment of this invention, it will be understood that many and various changes and modifications in form, arrangement of parts and details of construction thereof may be made without departing from the spirit of the invention and that all such changes and modifications as fall within the scope of the appended claims are contemplated as part of this invention.

The invention claimed and desired to be secured by Letters Patent is:

1. In combination, a structure for a heat exchanger comprising a bundle of heat exchange tubes arranged in two groups and means at the opposite ends of said bundle holding said tubes together and providing inlets and outlets therefor, said structure being free to float at at least one end thereof adapting said structure for relative outward and return inward movements of the ends thereof, from and to their relative normal positions, when said tubes are under thermal expansion and contraction respectively; and a control for effecting descaling of said tubes, including a tie rod extending longitudinally of each of said groups of tubes between said structure ends and connected at its ends to the adjacent ends of said structure and bearing against an intermediate portion of its correlated group of tubes, each of said tie rods being normally bowed before expansion of said tubes for effecting bowing of said tubes by lateral pressure against said intermediate portions due to straightening of said tie rods during expansion of said tubes, said control further including a telescopic bar-like member secured at its ends to the adjacent ends of said structure and having limited telescopic retractable movement for checking said structure ends inward movement due to contraction of said tubes when at said normal positions whereby further contraction will insure said tubes unbowing to their normal positions.

2. In combination, a structure for a heat exchanger comprising a bundle of heat exchange tubes arranged in two groups and means at the opposite ends of said bundle holding said tubes together and providing inlets and outlets therefor, said structure being free to float at at least one end thereof adapting said structure for relative outward and return inward movements of the ends thereof, from and to their relative normal positions, when said tubes are under thermal expansion and contraction respectively; and a control for effecting descaling of said tubes, including a tie rod extending longitudinally of each of said groups of tubes between said structure ends and connected at its ends to the adjacent ends of said structure and bearing against an intermediate portion of its correlated group of tubes, each of said tie rods being normally bowed before expansion of said tubes for effecting bowing of said tubes by lateral pressure against said intermediate portions due to straightening of said tie rods during expansion of said tubes, said control further including two parallel bar-like mem-

bers spaced on opposite sides of the axis of said structure for spacing said structure ends at said normal positions and for checking said structure ends inward movement due to contraction of said tubes when at said normal positions whereby further contraction will insure said tubes unbowing to their normal positions, and a tie member secured at its opposite ends to said bar-like members between the ends thereof, said tie member preventing bending of said bar-like members.

3. In combination, a structure for a heat exchanger comprising a bundle of heat exchange tubes arranged in two groups and means at the opposite ends of said bundle holding said tubes together and providing inlets and outlets therefor, said structure being free to float at at least one end thereof adapting said structure for relative outward and return inward movements of the ends thereof, from and to their relative normal positions, when said tubes are under thermal expansion and contraction respectively; and a control for effecting descaling of said tubes, including a tie rod extending longitudinally of each of said groups of tubes between said structure ends and connected at its ends to the adjacent ends of said structure and bearing against an intermediate portion of its correlated group of tubes, each of said tie rods being normally bowed before expansion of said tubes for effecting bowing of said tubes by lateral pressure against said intermediate portions due to straightening of said tie rods during expansion of said tubes, said control further including two parallel telescopic bar-like members spaced on opposite sides of the axis of said structure for spacing said structure ends at said normal positions each member being secured at its outer end to the adjacent end of said structure and having limited telescopic retractable movement for checking said structure ends inward movement due to contraction of said tubes when at said normal positions whereby further contraction will insure said tubes unbowing to their normal positions.

4. In combination, a structure for a heat exchanger comprising a bundle of heat exchange tubes arranged in two groups and means at the opposite ends of said bundle holding said tubes together and providing inlets and outlets therefor, said structure being free to float at at least one end thereof adapting said structure for relative outward and return inward movements of the ends thereof, from and to their relative normal positions, when said tubes are under thermal expansion and contraction respectively; and a control for effecting descaling of said tubes, including a tie rod extending longitudinally of each of said groups of tubes between said structure ends and connected at its ends to the adjacent ends of said structure and bearing against an intermediate portion of its correlated group of tubes, each of said tie rods being normally bowed before expansion of said tubes for effecting bowing of said tubes by lateral pressure against said intermediate portions due to straightening of said tie rods during expansion of said tubes, said control further including two parallel telescopic bar-like members spaced on opposite sides of the axis of said structure for spacing said structure ends at said normal positions each member being secured at its outer end to the adjacent end of said structure and having limited telescopic retractable movement for checking said structure ends inward movement due to contraction of said tubes when at said normal positions whereby further contraction will insure said tubes unbowing

to their normal positions, and a tie member secured at its opposite ends to said bar-like members between the ends thereof, said tie member preventing bending of said bar-like members.

5. In a heat exchanger having a shell, a tube sheet fixedly secured thereto, a tube bundle, and a floating tube sheet, control apparatus to descale the tubes comprising a pair of tie rods each secured to the tube sheets at its opposite ends, said tie rods being bent inwardly toward each other to form angles and being adapted to straighten under tension, a pair of plates disposed intermediate the tube sheets and orificed for the reception of the tubes, abutment means on each plate arranged opposite the adjacent tie rod angular portion, said abutment means being adapted to transmit lateral movement from the tie rod to the tubes to bend the same as the tie rods straighten out in response to tension caused by the movement of the floating tube sheet upon thermal expansion of the tubes, and a stop device to prevent the floating tube sheet from moving back beyond normal position under thermal contraction of the tube sheets thereby to insure the tubes unbowing to their normal position, such stop device including a first element rigidly secured to the fixedly secured tube sheet in abutting relation to the floating tube sheet in the normal position of the latter, and a second element rigidly secured to the floating tube sheet and arranged in telescopic relation to the first element.

6. In a heat exchanger having a shell, a tube sheet fixedly secured thereto, a tube bundle, and a floating tube sheet, control apparatus to descale the tubes comprising a pair of tie rods each secured to the tube sheets at its opposite ends, said tie rods being bent inwardly towards each other to form angles and being adapted to straighten under tension, a pair of plates disposed intermediate the tube sheets and orificed for the reception of the tubes, abutment means on the plates arranged to receive the tie rods at their angular portions, and a telescopic bar-like member disposed longitudinally of the tubes between the tube sheets and secured at its opposite ends to said tube sheets, the arrangement of the tie rods being such that they will straighten out under tension as the floating tube sheet moves away from the fixedly secured tube sheet under thermal expansion thereby forcing the pair of plates apart thereby to cause the tubes to bend, and the

arrangement of the bar-like member being such that upon the return movement of the floating tube sheet upon thermal contraction such member will function to stop such return movement of the floating tube sheet at normal position thereby to insure the tubes unbowing to their normal positions.

7. In a heat exchanger having a shell, a tube sheet fixedly secured thereto, a tube bundle, and a floating tube sheet, control apparatus to descale the tubes comprising a pair of tie rods extending longitudinally of said tubes, each of such rods being secured to the tube sheets at its opposite ends and being bent inwardly toward each other to form angles whose apices are opposite each other, a pair of plates disposed intermediate the tube sheets and orificed for the reception of the tubes, a shoulder on the inner side of each plate arranged to abut the adjacent tie rod at its angular portion, and a telescopic member disposed longitudinally of the tubes between the tube sheets, one element of such member being attached to the floating tube sheet and the other member being attached to the fixedly secured tube sheet, the arrangement of the tie rods being such that they will straighten out under tension as the floating tube sheet moves away from the secured tube sheet under thermal expansion and engage the shoulders of the plates to force such plates apart thereby to cause the tubes to bend, and the arrangement of telescopic member being such that upon the return movement of the floating tube sheet upon thermal contraction such telescopic member will close to form a stop for the return movement of the floating tube sheet at normal position thereby to insure the tubes unbowing to their normal straight positions.
